HYDROCARBON ENGINE

Filed Jan. 6, 1931

UNITED STATES PATENT OFFICE

ELLINGWOOD H. TOWLE, OF LARCHMONT, NEW YORK

HYDROCARBON ENGINE

Application filed January 6, 1931. Serial No. 506,903.

My invention relates to engines of the hydrocarbon type wherein a mixture of fuel and air is compressed and exploded in cylinders to cause reciprocation of the pistons and it is especially useful as applied to hydrocarbon engines used for driving automobiles, aeroplanes and other vehicles. The invention is applicable to a single cylinder engine as well as to various multi-cylinder types, in the latter case the invention being duplicated for each cylinder. With the understanding that the invention is adapted for use regardless of the number of cylinders, I have illustrated it in the drawing of the present case embodied in an engine having two cylinders merely by way of illustrating one example of the invention from which those skilled in the art will be able to apply the invention to various types of engines.

The present invention relates to a combination of parts which have a two-fold effect upon the engine. First, the present invention results in a more perfect application of oil for lubricating the reciprocating pistons, main shaft bearings and wrist pin; and this results in more perfect operation of the engine and reduction in wear. Secondly, the oil is applied to the walls of the piston in a manner which not only tends to cool the piston but also to maintain different parts of the top of the piston at a more uniform temperature.

It is well known that in a hydrocarbon engine of the explosive type that the greatest heat during combustion is created at some point over the top of the piston, generally near the center of the piston, so that the heat at the outer portions of the piston is considerably less than at this central point. I have found that instead of reducing the temperature of the piston as a whole, it is more important to reduce the temperature at the hottest point, so that the temperature throughout the piston will remain more nearly uniform during operation, so that expansion and contraction of the piston will be more uniform throughout. For this reason the oil taken from the crank casing is dashed or spread against the central portion of the piston to primarily reduce the temperature

at this point to bring it more nearly to the temperature of the other portions of the piston.

Where the oil is spread against the hottest portion of the piston head it is not necessary to depend so much upon the ordinary water or air cooling systems usually employed for cooling the engine and in fact I have been able to operate an engine embodying my invention without a radiator and without cooling means other than natural radiation. Notwithstanding the absence of the ordinary radiator and the circulating system I have been able to operate the engine with greater efficiency than the corresponding types of commercial engines. While pointing out that the use of the present invention may avoid the necessity of using the radiator or other outside cooling system, there is nothing in the present invention which would prevent the use of these where desired.

However, by eliminating the ordinary radiator and the water circulating system of the ordinary engine it is possible to reduce the weight of the engine and its operating parts as a whole and to avoid the difficulties heretofore encountered by defects in the ordinary cooling systems employed with hydrocarbon engines.

It is not as important a consideration to be able to operate an engine at relatively low temperatures as it is to maintain a more uniform temperature throughout the piston and cylinder because the latter condition makes it possible to obtain greater efficiency than where the mean temperature of the various parts of the engine is relatively low but where different portions have wide differences in temperature. The present invention, by applying oil from the crank case primarily to the portion of the piston which ordinarily is heated to the highest degree, makes it possible to keep this portion of the piston more nearly within the temperature range of other portions thereof, thereby making the expansion and contraction of the piston as a whole more uniform.

The oil which is projected against the top portion of the piston also sprays onto the skirt thereof so that the circulating oil has a tend-

ency not only to reduce the temperature at the hottest point but also to reduce the temperature of the piston as a whole including the wrist pin bearing.

5 By employing the present invention it is also possible to form the piston with a thinner top wall and thinner skirt than corresponding pistons now in general use, thereby facilitating dissipation of heat from the piston in addition to the advantage gained by reducing its weight.

10 By employing the present invention it is possible to use a piston of iron and to reduce the weight to a point where it compares more

15 favorably in regard to the weight factor with aluminum pistons. This is a desirable feature because iron pistons are advantageous over aluminum pistons except for the weight factor.

20 The method of circulating the oil shown herein partly for cooling purposes, also insures a more complete application of oil to the walls of the cylinders than is possible with the previous oiling systems. This is true 25 of the oil supplied to the main bearings of the crank shaft.

Another advantage of my invention is that the engine may be run for long periods before requiring changing of the oil in the crank

30 case. In most hydrocarbon engines the oil which strikes the under side of the head of the piston does so in small quantities and the excessive heat in the piston head causes the portion of the oil to be partly burned and as a re-

35 sult carbon particles are deposited on the under side of the piston head. Some of these carbon particles fall back into the oil and circulate with it and they tend to cut the various bearing surfaces. For this reason it is neces-

40 sary to renew the oil in the crank casing in most hydrocarbon engines about every five hundred miles of operation as otherwise the bearings will be injured by the grinding action of the carbon. In the present case there

45 is a sufficient supply of oil projected against the under side of the piston head to act as a cooling agent and prevent the temperature of the piston head from rising to a point where the oil will be destructively affected so that 50 the carbon particles referred to are not formed in the present engine even after operation over long periods such as a year.

Other features and advantages of the invention will be set forth in the following detailed description of one embodiment of the invention.

In the drawing forming part of this application,

55 Figure 1 is a vertical, sectional view through the middle of a hydrocarbon engine embodying my invention, the engine illustrated containing two cylinders,

60 Figure 2 is a vertical, sectional view taken 65 on the line 2-2 of Figure 1, and

Figure 3 is a sectional view taken on the line 3-3 of Figure 1.

As has been pointed out above, the present invention may be applied to a hydrocarbon engine having one or any greater number of cylinders and I deem it sufficient to enable those skilled in the art to apply the invention to illustrate the same in an engine having two cylinders, as shown in the accompanying drawing, but I do not limit the invention to application to an engine having any particular number of cylinders. The invention may be applied to different types of engines.

In the drawing I have shown a crank casing 1 of ordinary construction which, together with the lower portion of the cylinder block 2 forms a housing for the crank which is formed on the crank shaft 3. The cylinder block is shown as provided with two cylinders 4, 4' in which two pistons 5, 5' reciprocate, it being understood that the mixture of fuel and air is exploded within the cylinder chambers between the heads and the tops of the respective pistons in accordance with common practice in the art.

Each piston is shown as composed of a top horizontal wall 6, and of a cylindrical wall or skirt 7, extending downwardly therefrom and I have indicated both of these walls as being of less thickness than the walls of pistons as heretofore used in hydrocarbon engines because the present invention, as stated above, makes it possible to use pistons with thin walls, and therefore of light construction. However, I do not limit the application of my invention to a thin wall piston as distinguished from any other. Each piston reciprocates within its respective cylinder and each is provided with suitable rings 8 which may be of ordinary or any special form as my invention requires no modification of the piston rings but permits the use of any type. The bosses 9 extending inwardly from opposite sides of the skirt 7 form bearings for the wrist pin 10 on which the connecting rod 11 may be pivotally connected. Any type of wrist pin and bearing may be used as far as the present invention is concerned, but the connecting rod is drilled to provide oil grooves, as will be pointed out more in detail hereinafter.

Inasmuch as I have shown an engine having two pistons, I have shown the crank shaft 3 as provided with two crank throws, one for each piston, and it will be understood that in an engine having one cylinder there will be but one crank throw; or, if the engine has a greater number of pistons than that illustrated, there may be a corresponding increase in the number of crank throws on the crank shaft. In describing the engine illustrated, it may be pointed out that each crank throw is preferably formed of a disk 12 of circular form, preferably integral with the crank

shaft and disposed concentrically in relation to the axis thereof.

Between this disk and the diagonal member 13 of the crank throw there is a crank pin 14 which rotates around the axis of the crank shaft and on which the lower end of the connecting rod 11 is journaled.

While any type of connection may be employed for connecting the connecting rod and the crank pin, I have, by way of illustration, shown a common type. The lower end of the connecting rod is provided with a head 15 having a semi-circular recess 16 fitting onto the periphery of the crank pin 14; and from the head extends the lateral flange 17 to receive the coupling bolts. The lower half of the connection consists of a removable cap 18 which also has a semi-circular recess 19 conforming to the periphery of the crank pin and also having a lateral flange 30 provided with apertures to receive the connecting bolts therethrough. I have shown shims 21 clamped between the flanges 17, 30 and these are adapted to be adjusted laterally so that their inner edges 31 may be brought into close relation to the periphery of the pin 14 in order to prevent the oil from passing back and forth beyond the shims. The bolts 32 pass through the flanges 17 and 30 and 30 through the shims and serve to hold these parts in assembled relation around the crank pin.

The construction is the same for both pistons and the description applies to both alike, but to distinguish the parts unprimed numbers will be applied to those parts which relate to the left hand piston in Figure 1, and corresponding primed numbers will be applied to the parts which relate to the right hand piston in Figure 1.

The main bearing 33 for the crank shaft is shown as formed in the crank housing and there is an oil groove 34 formed in the wall of the housing, it being illustrated as disposed diagonally so that its upper end communicates with an oil pocket 35 formed between the outer wall of the housing and an inner partition or wall 36 which is shown as cast integral with the housing and spaced 50 from the outer wall to form the oil pocket. The oil groove 34 extends downwardly and communicates with the longitudinal groove 37 disposed along the face of the crank shaft and terminating at the inner end of the main bearing 33. The oil for the main bearing, therefore, travels from the pocket 35 downwardly through the oil groove 34 and thence into the oil groove 37 in which it is distributed onto the shaft within the main bearing. One 55 face of the disk 12 is provided with a circular groove 38 which extends inwardly within the disk and preferably at an angle to its axis, as shown in Figure 1. This groove is preferably formed eccentric to the axis of the crank shaft, so that when the parts are

in the position shown in Figure 1 the lower portion of the groove 38 is in position to receive the oil which flows out between the crank shaft and the main bearing. The purpose in making this groove eccentric is so 70 that the oil which is received from the end of the main bearing into the groove will, by reason of the revolution of the disk 12 be forced towards the portion of the groove which is furthest from the axis of the crank 75 shaft and which portion I have indicated by the numeral 39. This forcing of the oil towards one part of the groove is caused by centrifugal action, due to the revolution of the crank.

There is a port 40 which at one end communicates with the groove 39 of the disk and it projects diagonally through a portion of the crank pin and at the other end it communicates with the peripheral groove 41 85 formed in the head of the connecting rod around the crank pin.

The cap 18 which connects the connecting rod with the crank pin is provided with outlet ports 42 extending through the same for 90 the purpose of permitting oil to flow out of that portion of the groove 41 which is below the shims 21. I have shown a flange or rim 43 on one side of the disk 12 and as the latter disk dips into the oil 44 at the 95 bottom of the crank case the oil carried up on the surface of the disk is concentrated towards the rim 43 and it flies from this into the oil pocket 35 to be circulated in the manner hereinafter described.

Before the engine is started most of the oil will be in the lower part of the crank case as shown in Figure 1, and the several disks 12 dip into this oil. When the engine is started the crank shafts and the crank will 105 revolve and of course the pistons will reciprocate with the pistons and the cranks, an oscillating motion taking place in the connecting rod where it pivots on the wrist pin 10. During the operation of the engine the 110 rapidly revolving disks 12 which dip into the oil in the bottom of the crank case, carry up the oil on their surfaces and centrifugal action causes this oil to collect on the rim 43 and be thrown off toward the pocket 35 and 115 while all of the oil on the surface of the disk may not be thrown into the pocket, a sufficient proportion will be to carry out the circulation of oil as herein described.

The disk 12 will be continually picking 120 up the oil in the bottom of the crank case and throwing it into the pocket 35. The oil will flow from this pocket downwardly through the port 34 and into the oil groove 37 to supply the main bearing with lubricating oil. The oil will thence pass out of the end of the main bearing, i. e., between the surface of the bearing and the surface of the shaft 3 into the groove 39 in the revolving disk. Centrifugal action will cause the oil 130

which enters this groove to be thrust outwardly toward the eccentric portion 39 and into the port 40. The oil will be forced upwardly in the latter port and into the peripheral groove 41.

When the crank is in the upper position, as shown at the left in Figure 1, the oil which is forced up through the port 40 and into the groove 41 will pass upwardly through the central bore 47 extending lengthwise through the connecting rod. At the upper end of this bore and within the member 48 of the connecting rod the bore 47 communicates with a plurality of ports 49 which extend around the wrist pin 10 and which have their openings directed upwardly. The oil which travels up through the bore 47 passes into the ports 49 some of this oil serving to lubricate between the wrist pin and the member 48 of the connecting rod and the balance of the oil being projected in the form of drops, jets or streams against the under surface of the top wall 6 of the piston. After striking the top wall of the piston, the oil sprays laterally, and travels down the inner surface of the skirt 7. The oil which does not remain in contact with the piston or the cylinder will be thrown back into the bottom of the crank case and become part of the body of oil that is constantly present there.

The centrifugal action is sufficient to force the oil from the groove 38 upwardly through the port 40 when the crank pin is in the upper half of its stroke and the force also causes the oil to move upwardly through the bore 47 in the connecting rod and out through the ports 49 to spray against the piston in the manner just described. When the crank pin 14 together with the connecting rod 11 and piston are in the lower half of the stroke the bore 47 will be in communication with that half of the groove 41 which is below the shims and during this time the oil will continue to flow into the groove 41 but instead of flowing upwardly through the connecting rod it will flow downwardly through the release apertures 42 and fall down into the bottom of the housing. During this time there is no upward circulation through the connecting rod but the bore 47 of the latter nevertheless remains in communication with the groove 41 above the shims so that no oil can return or flow back. The purpose of the release apertures 42 is to permit continuation of the flow of the oil from the groove 38 in the disk 12 and through the port 40 so that when the crank pin is on the upper half of the stroke and the port 40 communicates with the portion of the groove 41 which is above the shims the oil will be in motion when this communication is established. Inasmuch as hydrocarbon engines are operated up to 2000 or even more revolutions per minute the period in which the crank is making the upper half of its revolution is very brief and if the vari-

ous oil channels were depleted of oil during the lower half of the stroke there would not be sufficient time for the channels to fill during the upper half of the stroke and for the oil to be projected from the top of the connecting rod against the piston.

Therefore, with the construction as herein shown and described there is oil at all times in the portion of the groove 41 which lies above the shims 21 as well as oil in motion in the port 40. Furthermore, there is always oil not only in the groove 41 but in the bore 40 so that as soon as communication is established between the bore 40 and the bore 47 of the connecting rod, which occurs during the upper half of the stroke, the oil will immediately be forced out of the upper end of the connecting rod to spray against the under side of the top wall of the piston. In other words, during the brief interval that the spraying action takes place, no time will be required to establish the flow through the various oil channels because the oil in the bore 47 is already in motion. By dividing the groove 41 into upper and lower portions by means of the shims 21, and by providing the relief apertures 42 it is possible to maintain circulation of the oil from the groove 38 through the port 40 and through a portion of the groove 41 in order to maintain a supply of oil within the port 40 ready for this oil to circulate through the upper half of the groove 41 and through the bore 47 of the connecting rod when the crank is making the upper half of its stroke. The oil which passes through the relief apertures 42 is performing at such times no useful purpose other than permitting the flow to continue as described. The portions of the shims which project into the groove 41 divide this groove off into upper and lower sections, the upper section communicating with the bore of the connecting rod while the lower section discharges through the relief apertures 42.

While the engine is in operation oil is continually picked up by the disk 12 and is thrown by the latter into the oil pocket 35 to be circulated in the manner above described.

The oil, after passing from the main bearing, enters the groove 38 and because of the eccentric position of this groove the oil is forced through the bore 40 and continues to circulate either upwardly through the connecting rod, during the upper half of the stroke, or downwardly through the relief apertures 42 back into the lower portion of the housing.

It will be apparent from the above that there is an ample supply of oil flowing to and through the main bearings and in addition there is a supply of oil flowing upwardly through the connecting rod to be splashed against the top wall of the piston. The centrifugal action of the oil in the eccentric groove 38 not only serves to propel the oil

upwardly through the connecting rod but the thrust of the connecting rod itself during the upper half of the stroke is added to the action taking place within the eccentric groove. It will be apparent that the flow of oil against the under side of the piston will be greater as the speed of the engine increases and this is a desirable factor because when the engine is running at high speed it is necessary to supply a greater flow of oil to carry away heat from the piston. After the oil which has been circulated against the piston is thrown down to the bottom of the crank casing it loses a large percentage of the heat which it received while in contact with the piston, through radiation through the walls of the crank casing.

When starting an engine in cold weather it is generally necessary to operate it at reduced speed for several minutes in order to permit the parts to warm up to a point where they will operate without damage before the engine is put under load.

Where the present invention is employed the engine may be brought up to operating temperature much more quickly than heretofore because of the rapid circulation of the oil in the manner here described. It is, in fact, desirable to operate the engine until the oil in the crank casing and the lower portions of the cylinders has begun to atomize or form a mist before the engine is called upon to operate a load, and this requires that the oil be heated to an efficient operating condition. Whereas in former practice it was necessary to run the engine idle, when starting in cold weather, for some minutes to bring the oil up to operating temperature, with the present invention this condition is reached after a few strokes of the engine, owing to the rapid circulation of the oil in contact with the hottest portion of the piston.

The present invention improves the circulation of oil between the parts which require lubrication and it also maintains more even temperature throughout the piston as well as serving to cool the latter as a whole and the bearings to a temperature approximating the temperature of the walls of the cylinders. Various changes and modifications may be made without departing from the spirit of my invention and I desire to cover all changes and modifications which come within the scope of the following claims.

Having described my invention, what I claim is:

1. In a hydrocarbon engine the combination of a cylinder, a piston reciprocating therein, a shaft having a crank throw, a connecting rod connected between said crank throw and said piston and having a longitudinal bore therethrough for the passage of oil and having an outlet for the oil at the

upper end of the connecting rod to cause the oil flowing through said bore to be projected against the under side of the piston head, said connecting rod having a head provided with a groove extending around the crank pin of said crank throw and communicating with said bore, means for dividing said groove into upper and lower compartments, said head having a discharge aperture for discharging oil from one of said compartments, said crank throw having a port extending into the crank pin thereof and communicating alternately with the compartments of said groove whereby said port is in communication with the bore of said connecting rod during the upper half of the piston stroke and in communication with said discharge aperture during the lower half of the piston stroke, and means for supplying oil to said second mentioned port. 75 80 85

2. In a hydrocarbon engine the combination of a cylinder, a piston reciprocating therein, a shaft having a crank throw, a connecting rod connected between said crank throw and said piston and provided with a longitudinal bore therethrough for the passage of oil, and having an outlet for the oil at the upper end of the connecting rod to cause the oil flowing through said bore to be projected against the under side of the piston head, said connecting rod having a head provided with a groove extending around the crank pin of said crank throw and communicating with said bore, means for dividing said groove into upper and lower compartments, said head having a discharge aperture for discharging oil from one of said compartments, said crank throw having a port extending into the crank pin thereof, and terminating at the periphery of said crank pin whereby as the crank throw revolves said latter port will communicate alternately with the compartments of said groove whereby said crank throw port is in communication with the bore of said connecting rod during the upper half of the engine stroke and in communication with said discharge aperture during the lower half of the engine stroke, and means for supplying oil to said second mentioned port. 90 95 100 105 110

3. In a hydrocarbon engine the combination of a cylinder, a piston reciprocating therein, a shaft having a crank throw, a connecting rod connected between said crank throw and said piston, said connecting rod having a longitudinal bore therethrough for the passage of oil and having an outlet for the oil at the upper end of the connecting rod to cause the oil flowing through said bore to be projected against the under side of the piston head, said connecting rod having a head provided with a circumferential groove extending around the crank pin of said crank throw, and communicating with said bore, said crank head having shims 115 120 125 130

- clamped between the members of said head and projecting into said groove to divide the same into upper and lower compartments, said head having a discharge aperture for discharging oil from one of said compartments, said crank throw having a port extending into the crank pin thereof and communicating alternately with the compartments of said groove whereby said crank throw port is in communication with the bore of said connecting rod during the upper half of the engine stroke and in communication with said discharge aperture during the lower half of the engine stroke whereby there may be a continuous flow of oil through said second mentioned port, and means for supplying oil to said latter port.
4. In a hydrocarbon engine having a crank casing provided with a main bearing, the combination of a crank shaft journaled therein and having a crank throw, a cylinder, a piston reciprocating therein, a connecting rod connected between said crank throw and said piston and provided with a longitudinal bore having an opening for directing oil flowing through said bore against the under side of the piston head, means forming a pocket to hold a supply of oil and means for conducting oil from said pocket to said main bearing, said crank throw being adapted to carry oil up from the lower portion of the crank casing and to discharge it into said pocket, said connecting rod having a head provided with a groove disposed around a crank pin of said crank throw and means for dividing said groove into upper and lower compartments, said crank throw having a groove to receive the oil passing from said main bearing and having a port communicating at one end with said groove and at the other end communicating periodically with the port in said connecting rod.
5. In a hydrocarbon engine having a crank casing provided with a main bearing, the combination of a crank shaft journaled therein and having a crank throw, a cylinder, a piston reciprocating therein, a connecting rod connected between said crank throw and said piston and provided with a longitudinal bore having an opening for directing oil flowing through said bore against the under side of the piston head, means forming a pocket to hold a supply of oil and means for conducting oil from said pocket to said main bearing, said crank throw being adapted to carry oil up from the lower portion of the crank casing and to discharge it into said pocket, said connecting rod having a head provided with a groove disposed around a crank pin of said crank throw, and means for dividing said groove into upper and lower compartments one of said compartments communicating with the connecting rod port and the other compartment having discharge ports, said crank throw having a groove to receive the oil passing from said main bearing and having a port communicating at one end with said groove and at the other end communicating with the groove in said connecting rod.
6. In a hydrocarbon engine the combination of a cylinder, a piston reciprocating therein, a shaft having a crank throw, a connecting rod connected between said crank throw and said piston and having a longitudinal bore therethrough for the passage of oil and having an outlet for the oil at the upper end of the connecting rod to cause the oil flowing through said bore to be projected against the under side of said piston head, said connecting rod having a head provided with a groove communicating with said bore, means for dividing said groove into separate compartments, said head having a discharge aperture for discharging oil from one of said compartments, said crank throw having a port extending into the crank pin thereof and communicating alternately with the compartments of said groove whereby said port is in communication with the bore of said connecting rod during the upper half of the piston stroke and in communication with said discharge aperture during the lower half of the piston stroke, and means for supplying oil to said second mentioned port.
- Signed at the city, county and State of New York this 4th day of October, 1930.
